(57) **CLAIM**

The design for a dewrinkle machine, as shown and described.

DESCRIPTION

FIG. 1 Top right perspective view.

FIG. 2 Front elevation (door open)

FIG. 3 Left side elevation

FIG. 4 Front elevation (door closed)

FIG. 5 Right side elevation; and,

FIG. 6 Top plan.

1 Claim, 1 Drawing Sheet

FIG. 1

FIG. 3

FIG. 2

FIG. 4

FIG. 5

FIG. 6
